J. H. REECE

PUNCH PRESS

Filed Oct. 30, 1920

UNITED STATES PATENT OFFICE.

JUAN H. REECE, OF JOLIET, ILLINOIS, ASSIGNOR TO REX STEEL STAMPING COMPANY, OF JOLIET, ILLINOIS, A CORPORATION OF ILLINOIS.

PUNCH PRESS.

Application filed October 30, 1920. Serial No. 420,610.

To all whom it may concern:

Be it known that I, JUAN H. REECE, a citizen of the United States, residing at Joliet, in the county of Will and State of Illinois, have invented certain new and useful Improvements in Punch Presses, of which the following is a specification.

The present invention has to do with improvements in punch presses and the like machines. The invention has reference to certain improvements in such machines and the mode of operation thereof which will greatly increase the capacity and tonnage of the machines.

In order that the features of the invention may be better understood and appreciated, I will first state that in the operation of certain kinds of punching machines such as machines for punching washers out of bar material, the capacity of the machine has in the past been limited by the speed at which the punched articles may be removed from the dies, since a new punching operation cannot commence until the material severed in the previous operation has been removed. This is particularly true in the case of horizontal punch presses in which the punched articles are carried away from the dies by the operation of the force of gravity. The capacity of such machines is absolutely limited by the rate at which the punched articles will fall away from the dies.

The main object of the present invention is to provide an arrangement for accelerating the removal of the punched articles so as to reduce the time interval between the punching operations. More particularly, an object in this connection is to accelerate this removal by the use of a fluid stream directed to a point where it will operate upon the punched articles as they leave the dies so as to accelerate their delivery; and still more particularly, another object of the invention is to make use of an air blast for this purpose.

Another object of the invention is to conserve the compressed air as much as possible by providing a valve mechanism or the like working in harmony with the other portions of the machine so as to deliver the air to the punched articles as a series of blasts properly synchronized with the movements of the dies, so that each blast of air

will come just at the right time to remove one of the punched articles.

Other objects and uses of the invention will appear from a detailed description of the same which consists in the features of construction and combination of parts hereinafter described and claimed.

Referring to the drawing:

Figure 1 shows a side elevation of a horizontal punch press to which the features of the invention have been applied; and

Fig. 2 shows a longitudinal section on enlarged scale through the air blast mechanism, and the valve for operating the same.

In the drawing the horizontal punch press is shown as comprising a frame 3 supported by legs 4 and having a yoke 5 within which are mounted the female die 6 and the male die 7. The frame also carries an operating shaft 8 driven by the pulley wheel 9. Upon said operating shaft are the eccentrics 10 and 11. The eccentric 10 carries a sleeve 12 which is connected to the arm of a bell crank lever 13 by means of a link 14, said bell crank lever being pivoted in the frame at the point 15. The other arm 16 of the bell crank lever works a reciprocating plunger 17 which has a knockout pin 18 working through the female die from the back side. This knockout pin 18 is for the purpose of ejecting the disks or other articles from the female die after the male die has been withdrawn. These articles then fall or are delivered into a basket or other container 19.

The eccentric 11 carries a sleeve 20 which operates the male die 7 back and forth through the medium of the plunger 21. The eccentrics are so timed that as the male die enters the female die the knockout rod 18 is in the backward position; and so that as the male die is withdrawn from the female die the knockout rod 18 is moved forward and ejects the article.

Machines of the general type of construction so far explained are well known and understood in the art. The features of the present invention relate to the provision of a blast or similar device 22 in position to accelerate the delivery of the articles. In the particular construction illustrated, this blast construction comprises a nozzle or opening 23 through which a blast of compressed air under relatively high pressure may be de-

2
livered, either continuously or as a series of intermittent puffs properly timed with respect to the operation of the other parts of the machine. In the particular construction 5 illustrated, the arrangement is such that the blast is delivered as a series of intermittent puffs. For this purpose a tube or pipe 24 is mounted in the frame above the female die, the bore 25 of said tube receiving compressed 10 air from the connection 26. A valve stem 27 extends through the bore and terminates in a poppet valve 28 at its inner end. When this valve is opened by moving the rod 27 forward, the compressed air is allowed to 15 pass through the chamber 29 and through the discharge slit 23 to operate on the severed disk or other article 30 as shown in Fig. 1.

The rear end of the rod 27 passes through a stuffing box 31 and a spring 32 operates on 20 said rear end to normally hold the rod in a backward position as shown by full lines in Fig. 2, and thus hold the valve normally closed.

The upper end of the arm 17 of the bell 25 crank 13 carries a finger 33 in position to operate on the rod 27 and thus open the valve in synchronism with the movements of the knockout rod 18.

I have found that by the use of an arrangement of this type it is possible to multiply the capacity of such machine several-fold, and in fact that their capacity is then limited only by the rate at which the dies 30 may be operated without overheating.

35 While I have herein shown and described only a single embodiment of the features of my present invention, still I do not limit myself to the same except as I may do so in the claims.

I claim:

1. The combination with the stationary female die and the reciprocating male die and the knockout device of a horizontal punch press, of a nozzle for compressed air adjacent to the delivery end of the female die 40 and adapted to deliver compressed air onto an article ejected from said die, suitable connections for delivering compressed air to said nozzle, a valve in said connections, and means for opening and closing said valve in 45 timed relationship to the operations of the male die and knockout device, to thereby deliver puffs of compressed air from said nozzle in synchronous and timed relationship 50 to the operations of the knockout device for ejecting punched articles, substantially as 55 described.

2. The combination with the stationary die and the reciprocating die and the knockout device of a horizontal punch press, one of 60 said dies being a male die and the other a female die, of a nozzle for compressed air adjacent to the delivery end of the female die and adapted to deliver compressed air onto an article ejected from said die, suitable connections for delivering compressed air to 65 said nozzle, a valve in said connections, and means for opening and closing said valve in timed relationship to the operations of the dies and knockout device, to thereby deliver 70 puffs of compressed air to said nozzle in synchronous and timed relationship to the operations of the knockout device for ejecting punched articles, substantially as described.

JUAN H. REECE.

Witness:

FRANK J. MAGEE.
